V. HAJEK

STREAM FLOW CONTROLLING INSTRUMENTALITY

Filed April 12, 1923

UNITED STATES PATENT OFFICE.

VLADIMIR HAJEK, OF PRAGUE, CZECHOSLOVAKIA.

STREAM-FLOW-CONTROLLING INSTRUMENTALITY.

Application filed April 12, 1923. Serial No. 631,577.

To all whom it may concern:

Be it known that I, VLADIMIR HAJEK, a citizen of Czechoslovakia, residing at Prague, Kgl. Weinberge, Czechoslovakia, have invented certain new and useful Improvements in Stream-Flow-Controlling Instrumentalities (for which I have applied for patent in Germany, filed July 26, 1921, and in Czechoslovakia on May 9, 1921), of which the following is a specification.

The present invention relates to stream-flow-controlling instrumentalities, and pertains more particularly to instrumentalities of this type wherein the movable element is capable of being raised bodily out of the channel and at the same time permit the element to be moved between channel-closing and channel-open positions to control the water level in the dam or the dike being controlled by the instrumentality. Structures of this type are generally of massive formation and are more or less difficult to move between the closed and open positions by reason of the extremely heavy weights that are required to be moved, this being true especially where the instrumentality is designed to control a channel of considerable width.

Among the objects of the present invention are to minimize the weight and the size of the instrumentality while maintaining the efficiency, and also to provide an arrangement which will permit the pressures of the confined water to aid in moving the instrumentality from its closed to its open position.

With these general objects in view and others that will appear as the nature of the invention is better understood, the same consists in the novel construction, combination and arrangement of parts hereinafter more fully described, illustrated in the accompanying drawings, and pointed out in the appended claims.

In the drawings forming a part of this application, and in which like designating characters refer to corresponding parts throughout the several views,

Figure 1 is an end elevational view of one form of flow-controlling instrumentality.

Figure 2 is a perspective view of the movable part or plate of the instrumentality. Figure 3 is an end elevational view of a modified form of the invention, showing a movement controlling arrangement employed with the dam plate,

Figure 4 is a vertical cross-sectional view of another form of the invention, showing a valved opening in the dam-plate,

Figure 5 is a vertical cross-sectional view of another form of dam-plate,

Figure 6 is a sectional view similar to Figure 5, showing the dam-plate in shifted position,

Figure 7 is a vertical cross-sectional view of another form of the invention,

Figure 8 is a detail-sectional view of a valve device which may be substituted for the movement-controlling arrangement of Figure 4.

Figures 1 and 2 show the dam-plate A in its flow-controlling position, the face of the plate being inclined upwardly to the horizontal and vertical in the direction of stream flow and thus slanting against the current of the water. The plate, in its rear, is provided with vertical supporting bars B at given intervals. These supporting bars, which can be constructed of concrete and integral with the dam-plate, have at their lower end metal insertions v which, in their turn find support upon the inclined metal plate a of a low prop D suitably arranged in the bottom of the river. These props protrude from the river bottom only a few centimeters.

Dam-plate A has at its lower end a cushioning member —t— which permits the dam plate to be closed watertight on the bottom of the channel. The supporting bars B can be connected with each other by means of transverse members q.

In Figure 3 the dam plate is shown as adapted to be shifted manually to an open position. Here the supporting bars B are stiffened by an iron construction, prop D being similarly braced by insertion X, so that the entire thrust or pressure is transmitted upon broad planes, as shown by little arrows X^a in the drawing.

At the upper ends of dam-plate A are pinions C' which engage curved racks O which are fastened to the shore-props. Thus, turning of the pinions C' acts to lay the dam-plate flat backward. For guiding of the lower end of the dam-plate, I provide rollers C which move upon segmental guiding rails O². The outer supporting bars B are provided with pinion-segments b which engage gearing formed on the bearing a.

The upper end of the dam-plate is shown as provided with an extension plate P, the movement of which, by shifting on its pivot

to a horizontal position or below the horizontal, serves to cause the water-level to lower from h' to h^2 .

Figure 4 is a dam-plate which moves to open position automatically. For this purpose the lower half 2, 3, of dam-plate A, held in closed position by the pressure of the water exerted in the direction R, is provided with an opening d which is closed 10 by a flap element or valve d' . Now, if this flap element is opened, the pressure of the water upon the lower half 2, 3, of the dam-plate is lessened and the dam-plate, because of the super-pressure upon the upper half 15 3, 4, turns flat backward. The rapidity of this turning portion of the upper half can be regulated by the size of opening d and the full or partly opening of the same.

Figure 5 represents an arrangement 20 whereby the supporting bars B are connected with each other by a transversely running wall C which stands perpendicularly to the dam-plate A. This wall C forms a part of the support for dam-plate A, and 25 also forms, with the dam-plate, the supporting bars and the bottom of the channel, a number of chambers the cross-sectional form of which is shown by the reference numerals 1, 2 and 3, and which are connected with each other through the open space beneath the supporting bars. Thus 30 they form in their effect a single chamber. By means of controllable passageways — f —, with which the shore-props are provided, 35 water from above the dam-plate can be brought into that chamber to produce a pressure therein on the side of the lower portion of the dam plate, so that the plate is subjected to different pressures above and 40 below the normal line of thrust, thus causing the dam plate to turn to its horizontal position.

In order to prevent this motion to be 45 too sudden, the wall C is provided with opening — e — just below dam-plate A. Now, if the size of the two circulation-channels f is so proportioned that the 50 quantity of water which flows through them equals the quantity of water which runs out of opening e , then only the pressure of the volume of water below the opening will be effective in the chamber beneath the transverse wall C. But if the quantity of water flowing through 55 the circulation-channels f , is greater than the quantity of water which escapes through opening e , then the pressure of the water rises in the chambers. Thus, any desired amount of force can be produced by varying 60 the size of the opening e in relation to the size of the circulation-channels f ; and the tilting of the dam-plate can be thus regulated. This construction also allows the use of the extension valve P.

Figure 6 shows a dam plate of the gen-

eral type of Figure 5 laid flat. The transversely running wall C dams the water at the height h^4 which should be only very little more than the height h^3 of the stream below the plate. In the drawing h' signifies the highest mark of the dammed water and h^2 shows the height of the water level after the extension flap P has been tilted.

Figure 7 shows a protective arrangement 75 which permits the plate of Figure 3 to be turned over into its horizontal position rapidly. To this end the props or shores are provided with a section of a rack M which turns upon a pivot J. Pinion C of the dam-plate engages this rack. Under ordinary operation, movement of the pinion causes dam plate A to tilt over because rack M is then held against edge m , n , of the prop by the rotation of the pinion. In case 85 of sudden pressure applied by the water upon the plate, it, together with the rack M, tilts over following the direction of the current.

Figure 8 represents a valve which may 90 be used to close the opening d of the dam-plate as described in Figure 4. This valve rests with its upper end upon pipe or tube r , the latter being provided with a pinion r' which engages rack r^2 on the lower side 95 of the valve. The lower end of valve N rolls, by means of roller k , upon dam-plate A and is supported by reinforcing strip f' and stopped by angle bar w .

As will be seen, the instrumentality is 100 practically produced by the movable or shiftable element referred to as the dam plate, and which is made up of the face plate or member A and the supporting formations B, and the stationary element or 105 formation D, the face member and the supporting formation being rigidly connected or formed integral so as to move as a unit with the movement provided by being fulcrumed on the element D.

This general arrangement, disclosed in various forms in Figs. 1 to 6, presents the supporting formation as projecting rearwardly from face member A in a direction that is normal to the plane of the face member, with the point of connection closer to the lower than to the upper edge of the face member, the position of the point of connection and the length of the supporting member being such that the lower and the upper edges of the face member and the point of contact between the supporting formation and the element D—which can be considered as a sustaining formation—are relatively positioned so that a cross-section of these parts 115 will present these points in substantial correspondence to the apices of an approximate right-angle triangle.

As will be understood, with such an arrangement and with the face member in its 120

inclined or channel-closing position, the fulcruming point of contact between the supporting and the sustaining formations—which corresponds in general to the apex of the right angle of the triangle—is in proximity to the bottom of that portion of the channel below the plate, so that there is but slight obstruction to the flow of water past this sustaining formation when the movable element is shifted to its horizontal position. This is of advantage in that the direction of thrust is applied to a portion of the sustaining member that is practically the bottom of the stream itself, and hence requires but a comparatively small amount of built thrust-sustaining construction as compared with the general type of instrumentality installations heretofore employed, especially under conditions where the instrumentality controls a stream of considerable width.

As will be understood this relative arrangement which positions the face member edges and the fulcrum point of the movable element more or less similar to the apices of a triangle produces an effect that enables the change in conditions that are set up when the element is first shifted from its closing position to be of service in permitting the pressures on the face of member A to be effective in shifting the movable element to its horizontal plane; the flow of water beneath the face member, as the latter begins its opening movement, reduces the pressure on the lower portion of the face member, so that the pressure on the upper portion of this member becomes superior and acts to carry the member to the horizontal plane.

In Fig. 5, this effect is extended in that it is not necessary to begin the movement of the movable element manually. In the form of Fig. 5, the development of pressure within the chamber or chambers between the face member and wall C, serves to produce the effect of a counter pressure on the side of the face member opposite that which is being subjected to the pressure of the confined water, the result being that there is set up a difference in pressure values between the upper and the lower portions of the face member, thus enabling the superior pressure present on the upper side of the thrust line to become active and start the movement of the member away from this closing position, this in turn bringing into action the results accruing from the flow of the water beneath the member.

What is claimed as new is:—

1. In the formation of dams, wherein the flow-controlling instrumentality is shiftable between channel-closing and channel-open positions, an instrumentality for this purpose including a shiftable element having a face member adapted to serve as a breast wall of the dam, said wall being shiftable

toward and from the bottom of the channel to permit water flow therebeneath at will, and a support-formation projecting normal to said face member in the direction of stream flow and movable with said member during shifting movement between such positions, said face member and support formation being rigidly connected, with the point of connection intermediate the upper and lower edges of the member and closer to the lower than the upper edge of such member to produce a greater projection of the member above than below the point of connection when the element is in its channel-closing position, and a stationary sustaining formation located at the bottom of the channel beyond the element, said support formation and the sustaining formation co-operating to maintain the element in its channel-closing position, said element, in such position, having its face member inclined upwardly to the horizontal and vertical in the direction of stream flow, a cross-section of the instrumentality presenting the upper and lower edges of the member and the point of contact of support formation and sustaining formation as relatively located in correspondence with the apices of an approximate right angle triangle of which said face represents the hypotenuse of the triangle, said support formation and the sustaining formation having relative fulcruming configurations to permit the element to shift so as to pass the face member from its inclined plane position to an approximately horizontal plane while maintaining removable contact between the support and sustaining formations, the element having its movements about the approximate point represented by the apex of the right-angle of the triangle.

2. An instrumentality as in claim 1 characterized in that the supporting formation includes a wall having its width extending in the direction of projection of such formation from the face member with the wall having a width generally less than the distance represented by the projection length of the supporting formation, the position of said wall relative to the face member being such as to produce a spaced relation therebetween to permit said wall to serve as a lower-level breast wall when the face member of the element is shifted into its inactive horizontal plane.

3. An instrumentality as in claim 1 characterized in that the supporting formation includes a wall having its width extending in the direction of projection of such formation from the face member with the wall having a width generally less than the distance represented by the projection length of the supporting formation, the position of said wall relative to the face member being such as to produce a spaced relation therebetween to permit said wall to serve as a

lower-level breast wall when the face member of the element is shifted into its inactive horizontal plane, said wall and face member in the channel-closing position of the element being operative to produce a chamber in open communication with a controllable passageway adapted to receive water from the dam at will to develop pressure within the chamber opposite the portion of

less projection of the face member to produce a counter-pressure effective on said portion of the face member.

In testimony whereof I affix my signature.
